ENER SETTING MACHINE

Original Filed Sept. 11, 1919.

UNITED STATES PATENT OFFICE.

PERLEY R. GLASS, OF WAYLAND, MASSACHUSETTS, ASSIGNOR TO UNITED SHOE MACHINERY CORPORATION, OF PATERSON, NEW JERSEY, A CORPORATION OF NEW JERSEY.

FASTENER-SETTING MACHINE.

Original application filed September 11, 1919, Serial No. 323,164. Divided and this application filed January 22, 1923, Serial No. 614,184.

To all whom it may concern:

Be it known that I, PERLEY R. GLASS, a citizen of the United States, residing at Wayland, in the county of Middlesex and State of Massachusetts, have invented certain Improvements in Fastener-Setting Machines, of which the following description, in connection with the accompanying drawings, is a specification, like reference characters on the drawings indicating like parts in the several figures:

This invention relates to fastener-setting machines and more especially to raceways for supplying fasteners to the setting mechanism. The invention is illustrated herein as embodied in an eyelet-setting machine of the type disclosed in my copending application Serial No. 323,164, filed September 11, 1919, of which this application is a division.

In the majority, if not all, of the prior commercial eyeletting machines provided with a hopper and a raceway to supply the eyelets, the entire length of the raceway as well as the hopper and its contents have constituted a load on the mechanism for reciprocating the delivery end of the raceway to present the eyelets to the setting mechanism. It has been proposed, however, to make the raceway in two sections and to connect the sections by a pivotal joint, so that the upper section and the hopper may remain stationary while the lower section alone is reciprocated to present the eyelets to the setting mechanism. In the proposed jointed constructions no provision has been made for adjusting the delivery end of the raceway to insure the necessary cooperative relation between it and the setting mechanism, although it is of primary and vital importance to insure such cooperative relation because without it the organization will not function at all.

In view of the conditions described above an object of this invention is to provide an improved raceway construction such that the advantages of a relatively light load on the operating mechanism may be obtained in addition to means for insuring the necessary cooperative relation between the delivery end of the raceway and the setting mechanism.

Accordingly a feature of the invention consists in a fastener-setting machine organization comprising a raceway the delivery end of which is movable relatively to its upper portion, and means for fastening the upper portion to the frame of the fastener-setting machine, said means having provision for adjustment whereby the necessary cooperative relation between the delivery end and the setting mechanism may be established.

Since it is commonly necessary to substitute one raceway for another, as when changing from one size or style of fastener to another, or for some other reason to detach the raceway from the machine, the attaching of the substitute raceway or the re-attaching of the temporarily detached raceway involves in each case the problem of re-establishing cooperative relation of the delivery end to the setting mechanism, for if the necessary adjustment is lost incidentally to detaching the raceway considerable time would be lost in making a new adjustment and in testing the assemblage to determine whether it is correct. In view of these considerations another object of the invention is to provide means by which an adjustment once accurately established may be potentially preserved while the raceway is detached, so that when it is re-attached it will become again effective and thereby avoid the necessity of again determining what it should be.

A feature of the invention related to the latter considerations consists in providing the raceway with adjustable elements adapted to remain with the raceway as integral parts thereof and adapted to cooperate with complementary attaching means having no adjusting capacity. These adjustable elements, even when the raceway is detached, never require a second adjustment for a given machine so long as they remain fixed relatively to the raceway, and they insure the desired cooperative relation regardless of the number of times the raceway may be detached and re-attached. Another advantage of this feature is that any number of interchangeable raceways may be substituted one for another repeatedly and for an indefinite number of times with but one

adjusting operation for each raceway, since each raceway preserves for itself the particular adjustment that has once been determined to meet the requirements of its individual cooperative relation to a particular setting mechanism.

The foregoing features and others are hereinafter described and claimed and are illustrated by the accompanying drawings.

10 Referring to the drawings:

Fig. 1 is a perspective view partly in section of a portion of an eyeletting machine including a raceway constructed in accordance with this invention. The point of view 15 of this figure is from the rear left-hand corner toward the front right-hand corner of the machine.

Fig. 2 is a perspective view partly in section of certain portions included in Fig. 1 20 as viewed from the front left-hand corner toward the rear right-hand corner of the machine.

Fig. 3 is a vertical section of the portions 25 forming the joint between the stationary section and the movable section of the raceway.

Fig. 4 is a sectional view, in the plane indicated by line 4—4 of Fig. 5, of the means forming the detachable connection between 30 the movable section of the raceway and its operating mechanism.

Fig. 5 is a section of the structure intersected by line 5—5 of Fig. 4.

Fig. 6 is a perspective view partly in section of one of the two anchorages by which the stationary section of the raceway is attached to the frame of the machine.

Fig. 7 is a sectional view of the other one of said anchorages.

40 Fig. 8 is a bottom plan view of the hopper and the disconnectible devices for operating the feeder therein.

According to the type of machine shown the raceway is arranged to deliver eyelets 45 to an inserting tool 10 above the work so that they will be inserted downwardly into the work and clenched underneath. The inserting tool is carried by a plunger which is arranged to slide up and down in stationary 50 bearings one of which is indicated at 12. The usual spindle 13 is provided for picking the eyelets from the raceway and holding them in position to be inserted and clenched. A portion of the work support is indicated 55 at 14. Since the setting mechanism is more fully shown and described in my aforesaid application Serial No. 323,164 the showing in Fig. 2 will probably suffice for present purposes.

60 A feature of the raceway hereinafter described is that only a relatively small part thereof is reciprocated to present eyelets to the tool 10. This feature, according to the 65 illustrated embodiment of the invention, is made possible by constructing the raceway in

sections and by joining them so that the upper section may remain stationary while the lower section reciprocates. As shown best by Fig. 1, the upper section 15 is affixed to the frame 16 of the machine while the lower section 17 is arranged to be reciprocated to present the eyelets to the inserting tool. As shown by Figs. 2 and 3 the sections 15, 17 are mortised one into the other and are connected by a pivot member 18. The axis of the pivot member extends from side to side of the machine so that the delivery end of the raceway may move from front to rear. The delivery end of the raceway is therefore provided with an outlet extending toward the front of the machine to permit the detachment of the leading eyelet in consequence of moving the delivery end to the rear.

The mechanism for reciprocating the lower section of the raceway is shown by Fig. 1. The delivery end is moved to the rear by a cam 20 and to the front by a compression spring 21. The cam is affixed to a shaft 22 and engages a roller 23 carried by a lever 24. The fulcrum member of this lever is indicated at 25. The roller 23 is maintained against the cam by the spring 21 which surrounds a rod 26 connected to the lever 24. The upper part of the lever carries a stud 27 by which pivotal connection is formed with the rear end of a link 28. The forward end of this link is pivotally connected to the lower raceway section by a stud 29. To facilitate connecting the link to and disconnecting it from the raceway the forward end of the link is formed with a U-shaped portion 30 (Fig. 5) adapted to embrace an eccentric portion 31 of the stud 29. The link may thus be connected and disconnected by swinging it about its rear pivot stud 27. The forward portion of the link projects beyond the U-shaped portion sufficiently to provide a handle 32, and this handle is made hollow to receive a spring follower 33 the function of which is to latch automatically the link in coupled relation to the movable section of the raceway. The follower 33 is adapted to yield to intentional coupling and uncoupling movement of the link to permit instantaneous disconnection and re-connection without requiring the use of a tool. The follower 33 is backed by a compression spring 34 and the latter is maintained under constant compression by a plug 35 secured into the end of the handle. The eccentric portion 31 of the stud 29 provides for adjusting the delivery end of the raceway from front to rear to give the coaxial register of the leading eyelet with the spindle 13, but if greater adjustment is required it may be obtained from the pivot stud 27 which also has an eccentric portion.

As shown by Fig. 4 the right-hand end of the stud 29 projects from the raceway and 130

is provided with a slot to receive a screw-driver for the purpose of effecting adjustment. That portion of the raceway section through which the stud extends is split so that it may be contracted by screw 36 to clamp the stud. Flanges 37, 37 are formed on the stud to engage the sides of the link to maintain the eccentric portion 31 in register with the link while adjusting the raceway angularly about the pin 41. The pivot stud 27 at the rear end of the link is clamped by a split portion 38 of the operating lever, said split portion having a clamping bolt 39, and the stud 27 being provided with a slot to receive a screw-driver so that it may be turned for the purpose of effecting adjustment.

As shown in Fig. 1, a block having spaced portions 40, 40 is fixed to the frame and said portions have flat confronting faces that embrace corresponding flat faces formed on the link 28. This device prevents the link from being sprung out of true when adjusting the raceway angularly about the pin 41, and maintains the forward end of the link against lateral displacement when the link is disconnected from the raceway. In the latter case the body of the fixed block serves to support the link. Furthermore, the portions 40, 40 brace the link against buckling and permit the use of a lighter link than otherwise would be practical.

The upper section of the raceway is fastened to the frame by a coupling pin 41 and by a stud hereinafter described, and may be adjusted about the axis of the pin to complete the registering of the delivery end with the spindle 13. The pin 41 is adapted to be inserted and withdrawn without requiring the use of a tool, and provision is made for holding it in coupling position so that it will not slip out of place excepting when it is intentionally withdrawn. As shown by Fig. 6 the pin is provided with an external annular groove 42, and one of the portions of the frame in which it bears is provided with a socket containing a spring follower 43. This follower is, to all intents and purposes, similar to that indicated at 33 in Fig. 3, and is backed by a compression spring 45 and a screw plug 44. The pin 41 extends from front to rear so that the raceway, in being adjusted about its axis, will shift the delivery end transversely of the lines of reciprocation. To provide for vertical adjustment of the raceway the section 15 is provided with an eccentric bushing 45 to receive the pin 41. Any convenient means such as a set-screw may be provided to prevent accidental turning of this bushing. A hexagonal head 46 is formed on the bushing to receive a wrench so that the desired adjustment may be made while the raceway is attached to the machine.

The position of the raceway with respect to angular movement about the pin 41 is

fixed by an adjustable connection shown in detail by Fig. 7 and included in Fig. 1. This connection comprises two fixtures 47 and 48 the first of which is fixed to the frame 16 and the latter of which is adjustably fixed to the raceway section 15 by screws 49. The screw-receiving holes 50 in fixture 48 are larger than the screws to afford lateral adjustment of the member 48 relatively to the raceway section 15, but when the screws are set up tightly their heads bind the parts 48 and 15 to each other so that they are in effect integral. The fixtures 47 and 48 are provided with holes for the reception of a screw stud 51, the adjustability of the fixture 48 relatively to the raceway section 15 providing for register of the holes notwithstanding any slight inaccuracy of machining that would be likely to occur. The stud-receiving hole in the member 48 is tapped, and the stud 51 is threaded to screw into it. When the stud is set up tightly its head is seated against one side of the fixture 47 and draws the fixture 48 against the other side. The advantages of the construction just described may be explained as follows: Assuming that a raceway is being attached for the first time, and that some adjustment is necessary to insure register of the delivery end with the spindle 13 of the inserting tool, fixture 48 will at first be loosened by unscrewing the screws 49 just enough to permit it to move laterally with respect to the raceway section 15. The raceway will then be pinned to the frame by inserting the pin 41. Fixture 48 will then be moved into register with fixture 47 so that the stud 51 may be inserted into both fixtures and screwed up tightly to bind them securely to each other, the raceway section 15 being still loose relatively to the fixture 48. The looseness or play thus afforded by the relatively large holes 50 will leave the raceway free to be adjusted within the limits of the holes in any direction.

The eccentric bushing 45 may then be turned to adjust the delivery end of the raceway to the desired level. Then the raceway will be adjusted to place the delivery end in register with the axis of the spindle 13, and while it is so held the screws 49 will be tightened to fix the raceway section 15 relatively to the member 48. For the purposes of this adjustment the screw 36 (Fig. 4) will be loose to enable the raceway section 17 to slide along the stud 29. The shaft 22 will then be turned by hand until the delivery end of the raceway moves to its extreme forward position, and if the center of the leading eyelet is not exactly in register with the spindle 13 the eccentric stud 29 will be turned to correct its position. It is to be observed that the raceway is provided with three adjustable elements, viz, the bushing 45, the block or plate 48, 125

and the stud 29, all of which remain as integral parts of the raceway when the latter is detached, and since their adjustments are not disturbed by detaching the raceway from the machine they insure correct register when the raceway is replaced.

In practice it is customary to provide a plurality of raceways for each machine so that when it becomes necessary to change 10 from one size or style of eyelet to another the operator has merely to substitute one raceway for another. Each raceway, having once been adjusted as described, need not thereafter undergo any change of adjustment in consequence of being replaced 15 temporarily by one or more other raceways.

The eyelets are supplied to the upper section of the raceway by a hopper 52 containing a rotary feeder having a plurality 20 of tufts 53 of bristles. This feeder and the ratchet wheel 54, arranged under the hopper, are connected by any suitable element extending through the bottom of the hopper. An oscillating arm 55 carries a pawl 25 56 which engages the ratchet wheel to turn the feeder step by step in one direction, the pawl being maintained in engagement with the ratchet by a spring 57. A pivot pin 58 projects downwardly from the arm 55 to 30 receive one end of a disconnectible connecting rod 59. The other end of the rod 59 is pivotally connected to an arm 60. A tension spring 61 running from the rear end of the connecting rod downwardly to an 35 anchorage on the arm 60 maintains the forward end of the rod normally in coupled relation to the pawl carrier 55, but when the raceway is about to be detached from the machine the connection between the 40 feeder and the connecting rod may be interrupted by merely depressing the forward end of the rod far enough to disengage it from the pin 58. The arm 60 is carried by one of the levers provided for operating 45 another part of the machine.

Having thus described my invention, what I claim as new and desire to secure by Letters Patent of the United States is:

1. The combination with a machine comprising a frame and fastener-setting mechanism, of a detachable unit comprising a raceway the lower part of which is movable relatively to the upper part, means for fastening said upper part to said frame, said 50 means having provision for adjusting the delivery end of the raceway to cooperate with said setting mechanism, and mechanism for operating said delivery end to present fasteners successively to the setting 55 mechanism.

2. The combination with a machine comprising a frame and fastener-setting mechanism, of a detachable unit comprising a raceway the lower part of which is movable 60 relatively to the upper part, means for fas-

tening said upper part to said frame, said means including one or more elements fixed to but adjustable relatively to the raceway and adapted to remain so fixed when the raceway is detached, and mechanism for 70 operating the delivery end of the raceway to present fasteners successively to the setting mechanism.

3. A raceway comprising an upper section, a lower section, a pivot connecting 75 said sections in end-to-end relation so that they may have relative movement, and a plurality of members fixed to but adjustable relatively to said upper section, said members having provision for cooperatively engaging suitable complemental members to attach the upper section rigidly to the frame of a fastener-setting machine.

4. A fastener-inserting machine comprising a reciprocatory raceway structure, an actuator and a connecting link arranged to impart reciprocatory motion thereto, a pivot member arranged to connect said link and said raceway structure, said raceway structure being adjustable lengthwise of 90 said pivot member, and fixed means arranged to brace said link so that it will not be sprung by adjusting the raceway structure lengthwise of said pivot member.

5. A fastener-inserting machine comprising a raceway structure one end of which is movable to and from a delivering position, an actuator for moving said end of the raceway structure to and from said position, an angularly movable link arranged to 100 transmit motion from said actuator to said raceway structure, an intermediate portion of said link having opposed flat faces, and stationary means arranged to engage said flat faces to brace the link against buckling. 105

6. A fastener-inserting machine comprising a reciprocatory raceway structure, an actuator for reciprocating said structure, a link arranged to transmit motion from said actuator to said structure, said link having a compound motion, and fixed means having flat confronting faces arranged to embrace an intermediate portion of said link to guide said portion.

7. A fastener-inserting machine comprising a sectional raceway one section of which is movable relatively to the next, an actuator for reciprocating said movable section, a link arranged to transmit motion from said actuator to said movable section and having angular motion as a component of its transmitting motion, and means arranged to guide an intermediate portion of the link so as to brace the latter against lateral displacement.

8. A fastener-inserting machine comprising a reciprocatory raceway structure, an actuator for reciprocating said structure, a link arranged to transmit motion from said actuator to said structure and having an-

gular motion as a component of its transmitting motion, means arranged to support an intermediate portion of the link when the latter is disconnected from the raceway structure, and means arranged to straddle an intermediate portion of the link so as to maintain the latter against displacement laterally from registering relation with said supporting means and the raceway structure.

9. A fastener-setting machine comprising a reciprocatory raceway element, a reciprocatory element for operating said raceway element, said elements being formed with cooperative coupling portions to be interengaged and disengaged, and automatic means for holding said coupling portions in cooperative relation in consequence of placing them in said relation.

10. A fastener-setting machine comprising a reciprocatory raceway element, a reciprocatory element for operating said raceway element, said elements being formed with cooperative coupling portions to be interengaged and disengaged, and spring-stressed means carried by one of said coupling portions for automatically restraining said coupling portions against uncoupling movement.

11. A fastener-setting machine comprising a reciprocatory raceway element, a reciprocatory element for operating said raceway element, said elements being formed with cooperative coupling portions to be interengaged and disengaged, and spring-stressed means carried by one of said coupling portions for automatically restraining said coupling portions against uncoupling movement.

12. A fastener-setting machine comprising a reciprocatory raceway element, a reciprocatory element for operating said raceway element, said elements being formed with cooperative coupling portions to be interengaged and disengaged, and spring-stressed latching means arranged to latch said portions automatically in coupled relation and adapted to yield to intentional uncoupling movement of said portions.

13. A fastener-inserting machine comprising a reciprocatory raceway structure for supplying fasteners, an actuator for reciprocating said structure, a link and pivot studs for transmitting motion from the actuator to the raceway structure, one of said studs being adjustably fixed to the raceway structure and having an eccentric portion for adjusting the raceway to a predetermined limit of motion.

14. A fastener-inserting machine comprising a frame, a jointed sectional raceway, adjustable means for reciprocating the delivery-end section of the raceway, and means for attaching another section of the raceway

to the frame, said attaching means being constructed and arranged to adjust the delivery end of the raceway transversely of its lines of reciprocation, and said reciprocating means being constructed and arranged to vary one of the limits of movement along said lines.

15. A fastener-inserting machine comprising a frame, fastener-inserting mechanism, a detachable unit including a raceway and one or more attaching members adjustably fixed thereto, means for cooperatively engaging said one or more attaching members to attach said unit to said frame, and mechanism for operating the delivery portion of said raceway to present fasteners to said inserting mechanism.

16. A fastener-inserting machine comprising a frame, a sectional raceway the sections of which are connected by a pivot-joint, adjustable means fixed to the upper section and having provision for rigid attachment to the frame, and means for oscillating the lower section.

17. A fastener-inserting machine comprising a frame, a sectional raceway the sections of which are connected by a pivot-joint, adjustable means for fastening the upper section rigidly to the frame, said means being constructed and arranged to adjust the delivery end of the lower section lengthwise of the axis of said joint, and means for oscillating the lower section about said axis.

18. A fastener-inserting machine comprising a frame, a raceway having upper and lower sections connected by a pivot-joint, a pivot member for connecting the upper section to the frame, adjustable means for fixing the position of the upper section with respect to angular movement about the axis of said pivot member, and means for oscillating the lower section.

19. A fastener-inserting machine comprising a frame, a raceway having upper and lower sections connected by a pivot-joint, a pivot member for connecting the upper section to the frame, the axis of said pivot member being transverse to that of said pivot-joint, adjustable means for fixing the position of the upper section with respect to angular movement about the axis of said pivot member, and means for oscillating the lower section.

20. A fastener-inserting machine comprising a frame, a raceway having upper and lower sections connected by a pivot-joint, cooperative fixtures fastened to the frame and to the upper section respectively, one of said fixtures being adjustable relatively to the element to which it is fastened, means for coupling said fixtures rigidly to each other, and means for oscillating the lower section.

21. A fastener-inserting machine comprising

ing a frame, a raceway having upper and lower sections connected by a pivot-joint, a pin for connecting the upper section to the frame, cooperative fixtures fastened to the frame and to the upper section respectively, said fixtures having cooperative stud-receiving holes arranged to occupy coaxial relation, a stud for occupying said holes to couple said fixtures, one of said fixtures being adjustable relatively to the element to which it is fastened to afford adjustment of the delivery end of the lower section, and means arranged to oscillate the lower section about the axis of said pivot-joint.

22. A fastener-inserting machine comprising a frame, a detachable raceway, means for attaching the raceway to the frame, and means for reciprocating the delivery end of the raceway, said attaching means including an adjustable element carried by the raceway for adjusting the delivery end of the raceway to the desired path of reciprocation and being constructed and arranged to maintain such adjustment potentially when the raceway is detached from the frame.

23. A fastener-inserting machine comprising a frame, fastener-inserting mechanism arranged therein, a detachable fastener-supplying structure, said frame and detachable structure having cooperative pin-receiving holes, a pin adapted to go into said holes to couple said structure to the frame, adjustable means arranged to fix the detachable structure with respect to angular movement about said pin, said detachable structure including a raceway portion arranged to oscillate about an axis transverse to that of said pin, and mechanism arranged to oscillate said raceway portion, about the first said axis, in cooperative relation to said fastener-inserting mechanism.

24. A fastener-inserting machine comprising a frame and a detachable raceway hav-

ing cooperative pin-receiving holes, a pin adapted to enter said holes to couple the raceway to the frame, and adjustable means for fixing the position of a portion of the raceway with respect to angular movement about the axis of said pin.

25. The combination with a fastener-inserting machine comprising a frame, mechanism for inserting fasteners, and raceway-operating mechanism, of a raceway consisting of an upper section and a lower section pivotally connected to each other, means for fastening two separate portions of said upper section to said frame, said means including two individually adjustable members each arranged to remain intact with said upper section to preserve their adjusted relation while the raceway is detached, and means for coupling said lower section to said raceway-operating mechanism.

26. The combination with a fastener-inserting machine comprising a frame, mechanism for inserting fasteners, and raceway-operating mechanism, of a raceway consisting of an upper section and a lower section pivotally connected to each other, disconnectible means for fastening said upper section to said frame, and disconnectible means for coupling said lower section to said operating mechanism, each of said means including an adjustable member for registering the delivery end of said lower section relatively to said inserting mechanism, and both of said adjustable members being arranged to remain intact with the raceway to preserve such register potentially while the raceway is detached from the frame.

In testimony whereof I have signed my name to this specification.

PERLEY R. GLASS.
